UNITED STATES PATENT OFFICE.

GEORGE R. AYRES, OF PHILADELPHIA, PENNSYLVANIA, ASSIGNOR TO WM. AYRES & SONS, OF PHILADELPHIA, PENNSYLVANIA, A FIRM COMPRISING LOUIS H. AYRES, WILLIAM G. AYRES, GEORGE R. AYRES, AND THE ESTATE OF WILLIAM M. AYRES.

WOVEN FABRIC.

1,310,902.

Specification of Letters Patent. Patented July 22, 1919.

Application filed February 23, 1917. Serial No. 150,581.

To all whom it may concern:

Be it known that I, GEORGE R. AYRES, a citizen of the United States, residing in Philadelphia, Pennsylvania, have invented 5 certain Improvements in Woven Fabrics, of which the following is a specification.

My invention relates to woven articles such as rugs, lap robes, carriage robes, and the like; and the object of my invention is to 10 provide these articles with a simple and cheap form of fringe. Articles of this character are more salable if provided with fringe but in the cheaper structures, where cotton instead of woolen or worsted warps 15 are employed, it is impossible to form fringe from the ends of said cotton warps.

The important object of my invention is the provision of rugs with a weft fringe; that is to say, a fringe made from the weft 20 or filling ends at the selvages of the woven fabric, after the selvages have been removed. In attempting any such procedure as this, it is necessary to provide selvage portions from which the warp threads can be removed prior to the twisting of the ends of 25 the weft to form the fringe. Additionally, however, these warps must be retained with the fabric and serve as a support for the wefts which are subsequently to form the 30 fringe, while the main body of the fabric as well as the selvage portions is being napped or teased to produce the desired fleece-like finished surface.

In carrying out my invention, I may employ warps of cotton or other cheap fiber, with woolen or worsted wefts, and the fringe is formed from weft ends at the selvage portions of the finished structure. In 35 this way, the width of the fabric as woven becomes the length of the rug or robe made therefrom, and the longer threads of such robe or rugs are the weft or filling threads; the warp threads being removed from such 40 selvage portions prior to twisting said weft or filling ends into fringe.

These and other features of my invention are more fully described hereinafter, reference being had to the accompanying drawings, in which:

50 Figure 1, is a diagrammatic view of an ordinary rug or robe in which the fringed ends are formed from the warp threads.

Fig. 2, is a similar view illustrating my

improved rug or robe in which the fringed ends are formed from the weft threads.

55

Fig. 3, is an enlarged view of a portion of a rug or robe made in accordance with my invention, illustrating the manner in which the selvages are formed.

Fig. 4, is a sectional view on the line 60 IV—IV, Fig. 3, and

Fig. 5, is a view similar to Fig. 3, showing the rug or robe after the warp threads adjacent the selvage portions have been removed and the ends of the weft threads 65 twisted.

Practically all rugs, whether of the floor variety or those employed to cover couches or used for personal wear, like steamer rugs, &c., and the various types of the so-called 70 automobile and carriage robes, blankets, &c., are provided with fringed ends or edges; such fringe being mainly employed for its esthetic or artistic value. Whatever the reason, it is highly desirable, and manufacturers aim to provide all rugs or robes 75 of the character described with fringed ends or edges.

In the more expensive rugs or robes in which both warp and weft are of wool or 80 worsted threads of substantially the same quality, the fringe formed integral with the rug or robe is made of the warp threads, and the method usually pursued is to stop the weaving operation when the end of a 85 cut representing a single rug or robe is reached, and then wind up with the woven part a portion of the warp threads sufficient to form the fringe ends for two rugs, and after the rugs are finished, the plain un- 90 woven portions of the warp threads may be cut through the center to form the fringe at the ends of the adjacent rugs. The free ends of said warps may then be twisted or left plain as may be desired.

95 In the manufacture of rugs in which the warps are of cotton, the filler or weft is usually made up of a woolen or worsted yarn of some weight, part or all of which may be of shoddy. In all instances, such 100 weft or filler has sufficient body to provide a proper fringe end integral with the rug, and the object of my invention is to provide a rug or robe having fringe made of weft or filling threads.

105 In the making of a rug in accordance with

my invention, the warps 1 will be of cotton, and the weft or filler 2 may be of a woolen or worsted yarn, or of shoddy, or of other form of yarn, and the structure of the rug 5 will be such that after the surface of the weft threads has been napped or teased in the usual manner to produce a fleecy or pile-like finish, the cotton warps will be completely hidden.

10 At the selvage portions where I propose to form the fringe from the weft ends, the warps 1^a are more or less widely separated, so that this portion will be relatively open or loose; permitting the ready removal of 15 these warps in order that the weft ends 2^a may be twisted to form the fringe.

Directly adjacent that portion of the woven structure which forms the body of the rug proper, I may introduce a few extra 20 warps 1^b, which may be set closer together, or I may employ so-called fine binding warps to closely tie the wefts to the warps at the point where the fringed ends begin, and at the margin of the selvages, I may 25 employ warps 1^c set relatively close together to maintain a proper selvage margin and, if necessary, insure sufficient body to permit the use of means to maintain the woven fabric taut and of proper width as it is being 30 woven.

As the weaving progresses, the woven material is wound on a roller in the usual manner; and when finished, it is napped or teased in the piece in any usual manner to bring 35 up the desired fleecy or pile-like surface.

After this is done, the formation of the fringe proceeds. To this end, the operator first removes from the selvage portions of the rug the loosely placed warps 1^a. After 40 these are removed, a plurality of the weft ends 2^a are then caught up by the operator and twisted in the manner illustrated in Fig. 5, and after such twisting, they may be tied as indicated at 5 in said figure. In the 45 twisted and tied condition, they are then preferably dampened with a suitable solution of size in water, and then subjected to heat and pressure for a short time, which will have the effect of setting the size and 50 causing the same to hold the twisted fringed ends in the position to which they have been brought by the twisting operation. After this has been done and the size has dried, the extreme outer ends of the wefts may be 55 cut off on the line $x-x$. After this is done, the fabric may be cut into sections of the size desired; the cut edges being folded over and properly bound or otherwise secured to prevent separation of the weft or filling 60 from the warps, as indicated at 6 in Fig. 2. If desired, the twisting, tying and setting operations on the weft ends might be carried on after removing the warp threads 1^c, but it is preferable to form and set the fringe 65 before this part of the selvage is removed.

While my invention has been designed more particularly for use in connection with relatively cheaper rugs, robes, and the like, wherein a cotton warp is employed as being more economical than the woolen or worsted warp, it is, nevertheless, available for more expensive rugs where it might be desirable to provide fringe for all four sides or edges of the same. To this end, the selvage portions could be woven with a series of cotton 75 warps set at relatively wide distances apart which might be removed after the weaving operation is completed in the manner above described. Such warp ends would then be twisted in the manner indicated, the twist 80 tied in, and then treated with a sized water and the subsequent application of heat and pressure to set the desired twist in the fringed ends.

I claim:

1. The process of forming fringe on rugs, which consists in providing warp threads, applying filler or weft threads and weaving the same substantially at right angles to said warp threads, the warps at the selvages 90 of the woven structure being disposed at relatively wide distances apart whereby a looser fabric is produced, teasing or napping the surfaces of the woven fabric, removing the warp threads from the selvage portions 95 of said sections, then twisting said weft ends, applying a medium to said twisted weft ends to set the same in their twisted condition, and finally cutting the woven fabric into sections of the desired size. 100

2. The process of forming fringe on rugs, which consists in providing cotton warp threads, applying filler or weft threads of wool and weaving the same substantially at right angles to said warp threads, the warps 105 at the selvages of the woven structure being disposed at relatively wide distances apart whereby a looser fabric is produced, teasing or napping the surfaces of the woven fabric, removing the warp threads from the 110 selvage portions of said sections, then twisting said weft ends, applying a medium to said twisted weft ends to set the same in their twisted condition, and finally cutting the woven fabric into sections of the desired 115 size.

3. The process of forming fringe on rugs, which consists in providing warp threads, applying filler or weft threads and weaving the same substantially at right angles to 120 said warp threads, removing the warp threads from the selvage portions of said sections, then twisting the weft ends at such selvage portions, applying a sized liquid to said twisted weft ends, and then applying heat and pressure to said sized ends to hold and set the twist imparted thereto. 125

4. The process of forming fringe on rugs, which consists in providing warp threads, applying filler or weft threads and weaving 130

the same substantially at right angles to said warp threads, teasing or napping the surfaces of the woven fabric, removing the warp threads from the selvage portions of 5 said sections, then twisting the weft ends at such selvage portions, applying a sized liquid to said twisted weft ends, and then applying heat and pressure to said sized ends to hold and set the twist imparted 10 thereto.

5. The process of forming fringe on rugs, which consists in providing warp threads, applying filler or weft threads and weaving the same substantially at right angles to said 15 warp threads, the warps at the selvages of the woven structure being disposed at relatively wide distances apart whereby a looser fabric is produced, teasing or napping the surfaces of the woven fabric, removing the warp threads from the selvage portions of said 20 sections, then twisting said weft ends, tying the said twisted weft ends, applying a sized liquid to said twisted weft ends, then applying heat and pressure to said sized ends to

hold and set the twist imparted thereto, and then forming the woven fabric into rung or 25 robe sections.

6. The process of forming fringe on rugs, which consists in providing warp threads, applying filler or weft threads and weaving the same substantially at right angles to said 30 warp threads, the warps at the selvages of the woven structure being disposed at relatively wide distances apart whereby a looser fabric is produced, teasing or napping the surfaces of the woven fabric, removing the 35 warp threads from the selvage portions of said sections, then twisting said weft ends, tying the said twisted weft ends, applying a sized liquid to said twisted weft ends, then applying heat and pressure to said 40 sized ends to hold and set the twist imparted thereto, and then forming the woven fabric into rug or robe sections.

In witness whereof I affix my signature.

GEORGE R. AYRES.
